CLAIM

The ornamental design for a wall clock mount, as shown and described.

DESCRIPTION

FIG. 1 is a top, rear left perspective exploded view of a wall clock mount according to the invention;

FIG. 2 is a top, rear left perspective assembled view thereof;

FIG. 3 is a rear elevational exploded view thereof;

FIG. 4 is a rear elevational assembled view thereof;

FIG. 5 is a front elevational assembled view thereof;

FIG. 6 is a front elevational exploded view thereof;

FIG. 7 is a left elevational exploded view thereof, the right elevational exploded view being a mirror image;

FIG. 8 is a left elevational assembled view thereof, the right elevational assembled view being a mirror image;

FIG. 9 is a top plan assembled view thereof;

FIG. 10 is a bottom plan assembled view thereof;

FIG. 11 is a top, front right perspective exploded view thereof; and,

FIG. 12 is a top, front right perspective assembled view thereof.

The phantom lines in FIGS. 1 and 2 are for illustrative purposes only to show the clock face to which the invention is attached and form no part of the claimed design.
